PIPE-LINE CLEANER LOADING AND
CLEANOUT DEVICE

William H. Roberts, Dallas, Tex.

Application July 9, 1946, Serial No. 682,428

11 Claims. (Cl. 15—104.06)

1

This invention relates to new and useful improvements in pipe line cleaner loading and clean-out devices.

It is well known that pipe lines used for conveying gases and other fluids over considerable distances accumulate quantities of paraffin and other foreign matter, corrosion and the like, on their interior walls. These accumulations interfere with efficient flow through the pipe line. As a result, it is now common practice to insert a cleaning projectile or "go-devil" in the pipe line and to propel the projectile through the pipe line by the pressure of the fluids being pumped therethrough. The practice customarily followed in inserting the cleaning projectile requires cutting the pipe line in two at the desired point, inserting the projectile into the line, and reconnecting the severed sections to permit the fluid pressure reapplied within the pipe line to flow the cleaning projectile through such line to remove the accumulations of foreign matters from the walls thereof. Such operations are expensive and dangerous, and may result in a considerable loss of gas or other fluid from the pipe line when the same is cut to permit insertion of the cleaning projectile.

It is, therefore, one object of this invention to provide a device permitting insertion of a pipe line cleaner in a pipe line without interfering with the normal use of and flow through such pipe line.

An important object of the invention is to provide a device arranged to permit the insertion of a cleaner projectile in a pipe line, and wherein the operation of inserting the cleaner projectile may be carried out without parting the pipe line or otherwise interfering with the normal operation and use of such line.

A further object of the invention is to provide a device of the character described which is so arranged that the cleaner projectile may be inserted and removed "under pressure," or without loss of pressure from the pipe line or stopping flow therethrough.

Still another object of the invention is to provide a device of the character described which is constantly ready for use after having once been installed in the pipe line, said device being capable of operation by a single attendant, whereby a plurality of devices may be operated by a single attendant and the cost of operation is materially reduced.

Another object of the invention is to provide devices of the character described which are adapted to be connected at a plurality of spaced

2

points in the pipe line to provide for selective cleaning of any desired section of the pipe line without interfering with the normal use thereof and flow therethrough.

5 A still further object of the invention is to provide, in a device of the character described, means for stopping the cleaner projectile flowing through the pipe line from upstream of such device, said means also serving to prevent injury or damage to the inserter mechanism.

Still another object of the invention is to provide a device of the character described wherein the relatively small quantities of gases or other fluids flowing through the pipe line which must

15 be released in operation of the device are confined and conveyed to remote points, whereby the danger of explosion or fire or the like is materially reduced, and loss of valuable fluids from within the line is substantially prevented.

20 A further object of the invention is to provide a device of the character described which is simple and rugged in construction, whereby costs of operation and maintenance are minimized.

Additional objects and advantages of the invention will readily be apparent from the reading of the following description of a device constructed in accordance with the invention, and reference to the accompanying drawings thereof, wherein:

30 Figure 1 is a view, partly in elevation and partly in section, of a device constructed in accordance with the invention and showing the loading barrel in loading position.

Figure 2 is a plan view of the device.

35 Figure 3 is a view similar to Figure 1, showing the loading barrel in the lowered position in alignment with the pipe line, and

Figure 4 is a fragmentary isometric view illustrating the shock absorbing stop means in position for stopping a cleaner projectile.

In the drawings, the numeral 10 designates an elongate upright rectangular case or housing having an inlet conduit 11 located substantially axially in one end wall and communicating with

45 the interior or chamber 12 of the housing, and having an outlet conduit 13 at the opposite end wall of the housing in axial alignment with the inlet conduit. The inlet and outlet conduits are provided with flanges 14 at their outer end, whereby the flanged end connectors 15 of a pipe line L may be bolted or otherwise suitably secured thereto to connect the housing in the pipe line so that fluid flowing through said pipe line may flow through the housing. Annular flanged seat 50 rings 16 are screw-threaded or otherwise releas-

ably mounted at the inner end of the inlet conduit and at the inner end of the outlet conduit, and such rings abut tightly against the end walls of the housing to provide seating surfaces at the inlet and outlet conduits for a purpose which will be hereinafter described.

An elongate tube or barrel 17 having an axial bore 18 of a size substantially the same as that of the pipe line L is disposed longitudinally of the housing and is adapted to be moved vertically therein. The tube 17 is externally enlarged at each end, and vertically extending operating rods 19 are welded, threaded, or otherwise suitably secured to the enlarged portions of the tube and extend upwardly through the upper wall of the housing. Stuffing boxes 20 having packing 21 are held securely therein by gland members 22, prevent fluid pressure leakage between the operating rods and the upper wall of the housing.

The upper portion of each operating rod is externally screw-threaded and gear wheels 23 having axial internal screw threads corresponding to the thread on the operating rod mesh with the threads on said rod to actuate the same. The gear wheels are rotatably mounted on brackets 24 secured to the upper surface of the housing. If desired, an elongate tubular cover 25 may be slipped over the extreme upper portion of each operating rod above the gear wheels and rest upon and be supported by said gear wheels.

A large drive gear 26 is rotatably mounted on a bracket 27 on the upper side of the housing and is arranged to mesh with the external gear teeth of the gear wheels 23 to cause the gear wheels to turn in unison. A large hand wheel 28 is connected to or formed integral with the drive gear 26, whereby an attendant may rotate the hand wheel to rotate the drive gear and, in turn, rotate the gears 26. Due to the fact that the large drive gear meshes with both the smaller gear wheels 23, said gear wheels will be turned in unison in the same relative direction. As the small gear wheels 23 are rotated, it is obvious that the threads in the axial openings of such gear wheels will rotate with respect to the operating rods to move the operating rods longitudinally. Therefore, the hand wheel 28 may be manipulated by an attendant to turn the drive gear 26, to drive the gear wheels 23, and thereby raise or lower the operating rods and the tube or barrel connected thereto.

Wedge rings 30 are arranged to be interposed between the ends of the tube 17 and the seat rings 16 to provide a fluid tight seal therebetween. The inner surface of each wedge ring is flared outwardly and downwardly from its upper end, as clearly shown in Figures 1 and 3, and is adapted to engage a similar angular or inclined face on the ends of the tube or barrel 17. While the ends of the tube may simply be formed to correspond to the inner faces of the wedge rings, it is preferable that a flanged replaceable seating face member 31 be threaded onto each end of said tube in such a manner that the seating face is disposed at the same angle as the inner surface of the wedges. A spacer washer 32 is interposed between the ends of the tube and the inwardly directed flange or seating face of each face member to provide for longitudinal adjustment of the length of the tube to positively assure seating the same in fluid tight relationship with the wedge rings 30. By changing the thickness of the washer 32, wear of the wedge ring or of the face member may be compensated to positively assure alignment of the bore 18 of

the tube with the inlet and outlet conduits when the tube is in the position shown in Figure 3.

The wedge rings are raised or lowered by means of an elongate operating screw or rod 33 which is welded, threaded, or otherwise secured to the side of each ring at its upper or narrowest portion. The operating screw rod extends upwardly through the upper wall of the housing, and leakage of fluid pressure therebetween is prevented by a stuffing box 34 having packing 35 securely compressed therein by a gland member 36. An internally screw threaded bushing 37 is rotatably secured in a bracket 38 mounted on the upper surface of the housing and the internal screw threads of the bushing are arranged to mesh with the external screw threads on the operating rod 33. A hand wheel 39 connected to or formed integral with the bushing 37 may be manipulated to rotate the bushing to cause longitudinal adjustment of the screw rods, whereby the wedge ring 30 may be raised or lowered within the housing.

Arcuate stop members 41, welded or otherwise suitably secured to the walls of the housing just below the seating rings 16, limit downward movement of the wedge rings and, consequently, also limit downward movement of the tube or barrel 17, whereby the wedge rings and the tube are positioned in alignment with the inlet and outlet conduits.

A loading opening 45, having a replaceable seat ring member 46 screw threaded or otherwise suitably secured therein, is formed in the outlet end wall of the housing above the outlet conduit 13. This opening is normally closed by a trap door or hatch 47 which may be suitably hinged or otherwise swingably mounted on the housing and is normally securely clamped or locked in closed position. An exhaust vent pipe 48 having a valve 49 therein is threaded but may be welded into the trap door or hatch 47 and provides means for venting fluids from within the housing at that point. An annular seat ring 50 is replaceably mounted on the inlet end wall of the housing above the inlet conduit 11 and in horizontal alignment with the loading opening 45.

The wedge rings 30 are adapted to seat on the seat rings 46 and 50 to seal between the ends of the tube 17 and the end walls of the housing as shown in Figure 1. When the tube or barrel and the wedge rings are in the position shown in Figure 1, gas or other fluid contained within the bore 18 of the tube may be exhausted or permitted to escape therefrom by means of a vent line 51 communicating with the interior of the housing substantially axially of the seat ring 50. A vent valve 52 connected in the vent line normally prevents escape of gases from within the housing, but may be opened to permit exhausting or venting the gases therefrom if desired. The gases or any fluids so vented or exhausted are conducted to a remote safe point by means of an exhaust pipe 53 communicating with the vent line 51 and the vent valve 52.

After the pressure fluids within the bore of the tube 17 have been exhausted or vented through the vent line 51, the trap door 47 may be opened to permit access to the bore of the tube, whereby a cleaner projectile C of any desired suitable type may be inserted within the bore of the tube to the position shown in Figure 1. The trap door 47 is then securely closed. In order to prevent the admission of air into the pipe line, some of the pressure fluids which are flowing through such pipe line are conducted by

means of a by-pass pipe 54 having a by-pass valve 55 therein from the inlet conduit 11 to the bore of the tube to expel the air therefrom and to equalize the pressure within the bore of the tube with the pressure in the pipe line and the interior or chamber 12 of the housing. This is accomplished by closing the vent valve 52, opening the exhaust valve 49, and then opening the by-pass valve 55. The pressure fluids within the pipe line will flow through the by-pass pipe 54 to the bore of the tube and longitudinally therethrough to the exhaust or bleeder line 48. Thus, the pressure fluids will expel the air from within the bore of the tube outwardly through the exhaust or bleeder pipe 48. When the air has been ejected, the valve 49 is closed to trap the pressure fluid being conducted to the bore of the tube through the by-pass line 54. When the pressure within the bore of the tube becomes equal to the pressure of the fluid within the pipe line, the valve 55 is closed. The fluid pressures of all the elements within the housing are then in balance or fully equalized.

The tube 17 may then be lowered into alignment with the inlet and outlet conduits to permit the cleaner projectile to flow through the pipe line to clean the same.

In lowering the tube to the position shown in Figure 3, the wedge rings 30 are first lowered by rotating the threaded bushings 37 to move the screw rods 33 downwardly, whereby said wedge rings will be lowered into engagement with the stop members 41. After the wedge rings have been so lowered, the hand wheel 28 is turned to turn the drive gear 26 to cause rotation of the gear wheels 23. Rotation of the gear wheels causes the operating rods 49 to be moved downwardly to lower the tube into alignment with the inlet and outlet conduits. The wedge rings 30 may be raised slightly, if necessary, to assure a positive fluid tight seal between the ends of the tube 17 and the seat rings 16, whereby pressure fluids flowing through the pipe line L are directed solely through the tube and cannot enter the chamber 12 of the housing. The cleaner projectile C is then forced or flowed out of the tube through the outlet conduit and on downstream through the pipe line L by the pressure of the fluids flowing through said pipe line.

With the tube or barrel 17 in the lowered position, the accumulation of matter which has been cleaned from the bore of the pipe line and has flowed into the interior of the housing may be removed therefrom by opening a clean-out valve 60 which is connected in a clean-out line 61 communicating with the bottom of the housing and with the exhaust line 53. When the fluid tight seal has been formed between the ends of the tube 17 and the inlet and outlet conduits, fluid pressure therein will be excluded from the housing chamber and the pressure fluid within the chamber may flow outwardly through the clean-out line to a remote point, carrying with it such fluid portions of the foreign matter deposited within the housing as will readily flow therefrom.

In order to fully or completely clean the interior of the housing a clean-out opening 62 is formed in the outlet end wall below the outlet conduit 13. This clean-out opening is normally closed by a trap door or hatch 63 which is hingedly connected or otherwise swingably secured to the end wall of the housing and is arranged to be normally securely clamped or fastened in position closing such opening. A bleeder pipe 64

having a bleeder valve 65 therein is connected to the trap door and communicates with the interior of the housing for a purpose which will be hereinafter described.

- 5 After the pressure fluids within the interior 12 of the housing have been exhausted or vented through the clean-out line 61 to reduce the pressure within the housing to approximately atmospheric pressure, the clean-out trap door 63 may be opened to provide access to the interior of the housing for completely and adequately cleaning the same. Likewise, any cleaner projectile which has been stopped and deposited within the interior of the housing in the position shown in Figure 3 may be removed therefrom through such clean-out opening 62.
- 10
- 15

When the housing has been cleaned and the cleaner projectile removed from the bottom thereof, the clean-out door is securely closed and the bleeder valve 65 is opened. The air which has entered the housing during the cleaning process is expelled therefrom by pressure fluids conducted into the chamber through a by-pass line 67 having a by-pass valve 68 therein. The by-pass line 20 communicates with the interior of the inlet conduit 14 and is connected to the clean-out pipe 61 between the valve 60 and the housing, as clearly shown in Figures 1 and 3. Pressure fluids from within the inlet conduit will flow through 25 the by-pass line 67 and the clean-out line 61 to the interior of the housing and will expel or 30 eject any air which has accumulated therein by forcing the same outwardly through the bleeder pipe 64 connected in the clean-out hatch. After 35 the air has been completely or sufficiently ejected from the housing, the bleeder valve 65 is closed and the pressure fluid from the inlet conduit is permitted to continue to flow into the housing 40 until the pressure within the housing is equal to the pressure in the pipe line, whereupon the by-pass valve 68 is closed.

The tube or barrel 17 may then be raised to the position shown in Figure 1 for reloading with a cleaner projectile in the manner previously described.

The operation of raising the tube is the reverse of the lowering operation. The large hand wheel 28 is first rotated to turn the drive gear 26 to cause the gear wheels 23 to turn. The turning of 50 the gear wheels 23 causes the operating rods 49 to be raised to lift the barrel into alignment with the seat rings 46 and 50 in the upper portion of the housing. The threaded bushings 37 are then rotated by turning the hand wheels 39 to lift the 55 screw rods 33, whereby the wedge rings 30 are raised to the position shown in Figure 1 and are in tight sealing engagement with the end of the barrel and with the seats 50 and 46 at each end of the housing. With the tube or barrel in this 60 raised position, the pressure fluid within its bore may be exhausted or vented, in the manner already described, to permit insertion of a cleaner projectile for repetition of the pipe line cleaning operation.

Under normal conditions, it is preferable that a cleaning device be connected in the pipe line at each of a number of relatively closely spaced points, whereby any desired section of the line may be cleaned selectively without the necessity of flowing the cleaning projectile through the entire length of the pipe line. Also, such installations permit trapping and removal of the dislodged foreign matter at each of the devices, whereby large accumulations of removed or dis-

lodged foreign matter are prevented and the pipe line may be more readily kept cleaned.

If desired, the tube or barrel 17 may be positioned in alignment with the inlet and outlet conduits and the pipe line in the manner shown in Figure 3, whereby the cleaner projectile from a point upstream may flow completely through the housing to a point further downstream. However, such operation is not generally desirable and some means must be provided for stopping the cleaner projectile at the housing in such a manner that it may be removed therefrom for repair or adjustment and reinserted for further use.

When it is desired to stop the cleaner projectile from upstream at any particular housing, the tube or barrel 17 is lifted to the position shown in Figure 1 and the cleaner projectile is permitted to flow into the interior or chamber 12 of the housing through the inlet conduit 11. For both stopping the cleaner projectile and preventing damage to the seat 16 at the outlet conduit by the projectile flowing into the housing and striking said seat, a stop or bumper ring 10 is mounted in a bonnet 11 affixed to the side of the housing and having an opening 12 providing for communication with the interior of such housing. The bumper ring has substantially the same external diameter as the seat ring 16 but has a bore 13 which is smaller than the bore of the conduit outlet and the pipe line, whereby said stop or bumper ring will positively be engaged by the cleaner projectile to prevent said projectile from flowing outwardly of the housing through the outlet conduit.

A plurality of projecting resilient lugs 14, formed of hard rubber, synthetic rubber, or other suitable material, are secured to the rear surface of the bumper ring and are arranged to engage the seat 16 to protect the same against shock or scarring when the projectile strikes the bumper ring. The lugs 14 also space the bumper ring from the seat ring 16 whereby the flow of fluids through the device is unrestricted. The spaces between the lugs and between the bumper ring and the seat ring, plus the opening 13 through the bumper ring, are at least equal to and preferably greater than the cross sectional area of the bore of the outlet conduit 13 whereby unrestricted flow through the housing is permitted when the bumper ring is in the position shown in Figure 4.

An elongated screw rod or shaft 15 is connected to the edge of the bumper ring and extends outwardly through the end of the bonnet 11 and through a stuffing box 16 having packing 17 securely held therein by a gland member 18. An internally screw-threaded bushing member 19 is threaded onto the outer end of the screw rod and is rotatably secured in a bracket 20 provided on the outer end of the bonnet. A hand wheel 21 connected to or formed integral with the bushing provides for ready manipulation of said bushing. Manifestly, when the bushing is rotated in one direction the screw rod 15 will be moved longitudinally to move the bumper ring from its retracted position within the bonnet 11 (Figure 2) to its protective position shown in Figure 4, and when the bushing is rotated in the opposite direction the rod will be moved to retract the bumper ring into the bonnet and out of the housing chamber.

The bumper or stop ring 10 is preferably maintained in the position illustrated in Figure 4, wherein it serves to protect the seat 16, during all periods in which the barrel or tube 17 is in the raised or upper position shown in Figure 1, but

is withdrawn into the bonnet 11 when the tube or barrel is to be lowered into alignment with the pipe line as shown in Figure 3.

If desired, and it is preferable, an inspection and service plate 20 may form one entire side wall of the housing 10. In such event, the plate 20 will be securely connected to the end and top and bottom walls of the housing by cap screws 21 extending through the plate into said end and top and bottom walls. A packing gasket 22 interposed between the inspection plate 20 and the edges of the end and top and bottom walls of the housing prevents fluid pressure leakage therebetween. When the housing is provided with such an inspection plate, the entire internal working parts of the pipe line device are readily accessible for repair or replacement or cleaning, as desired or necessary. In order to remove the inspection plate, the tube or barrel 17 must be positioned in sealed alignment with the inlet and outlet conduits or all flow through the pipe line connected to the housing must be closed off by valves (not shown) upstream and downstream of the housing.

From the foregoing, it will readily be seen that a pipe line cleaner loading and clean-out device has been provided which permits insertion of a cleaner projectile into the pipe line without interfering with the normal use of or flow through such pipe line, and wherein the cleaner projectile may be inserted without the necessity of parting the pipe line or closing off the flow therethrough or losing pressure therefrom. It will also be seen that the cleaner projectile may be inserted in the pipe line "under pressure," or without loss of pressure from pipe lines other than such relatively small quantities of gases or other fluids as may be trapped within the housing of the device and that such quantities of gases as are permitted to escape from the housing are conducted or conveyed to a remote safe point, whereby the danger of an explosion or fire or the like is materially reduced and the loss of valuable fluids is substantially eliminated. It is also manifest that pipe line cleaner loading and clean-out devices may be connected at spaced points in a pipe line to provide for selective cleaning of any desired section of such pipe line without interfering with the normal use thereof or flow therethrough, and without interfering with the use of other sections of said pipe line. It will further be seen that the device is so simple and rugged in construction that it is capable of operation by single attendant, whereby a plurality of the devices may be served by such single attendant and the cost of operation thereby materially reduced. It will also be seen that once the pipe line cleaner loading and clean-out device has been connected in the pipe line it is constantly ready for use for inserting a cleaner projectile without cutting the pipe line or otherwise interfering with the operation and use of the line and without the danger of fire and explosion which is otherwise attendant upon such parting or cutting of the line.

The foregoing description of the invention is explanatory only, and changes in the details of the construction illustrated may be made by those skilled in the art, within the scope of the appended claims, without departing from the spirit of the invention.

What I claim and desire to secure by Letters Patent is:

1. A pipe line cleaner loading and clean-out device including, a housing having a flow chamber

therein with an inlet and an outlet adapted to be connected with a pipe line, tubular loading means movable in the chamber of the housing into and out of communication with the inlet and outlet, said housing chamber serving as a conductor for fluids from the inlet to the outlet thereof when said tubular loading means is moved out of alignment with said inlet and outlet, means for moving the loading means in said chamber, openable and closeable means in the housing spaced from the inlet and outlet and in a position providing access to the loading means when said loading means is out of alignment with the inlet and outlet of the housing to permit a cleaner element to be inserted therein while fluids are flowing through the housing chamber exteriorly of said loading means, said loading means being movable into communication with the inlet and outlet of the housing to permit the cleaner element to flow from the loading means into the pipe line to clean the same, and sealing means adjustable from exteriorly of the housing for sealing between the ends of the tubular loading means and the housing when said loading means is in alignment with the housing inlet and outlet and when said loading means is in alignment with said openable and closable access means and spaced from the inlet and outlet.

2. A pipe line cleaner loading and clean-out device including, a housing having a chamber therein and having an inlet conduit and an outlet conduit communicating with said chamber, said housing being adapted to be connected with a fluid pipe line whereby fluid flowing through such pipe line may flow through the inlet conduit into the chamber of the housing and outwardly therefrom through the outlet conduit, a tubular loading member movable within the chamber of the housing and having a flow passage therethrough, means operable from exteriorly of the housing for moving the loading member within the housing chamber to move the flow passage of said loading member into and out of communication with the inlet and outlet conduits, the housing chamber serving as a conductor for fluids when said loading member is moved out of alignment with the inlet and outlet conduits, and openable and closeable means providing access to the flow passage of the loading element when the same is out of communication with the inlet and outlet conduits and the fluids are flowing through the housing exteriorly of said loading member to permit insertion of a cleaner member into said flow passage from exteriorly of the housing, whereby said cleaner member may pass from the flow passage of the loading member through the outlet conduit to the pipe line when the loading member is moved to position the flow passage in communication with the inlet and outlet conduits of the housing, and sealing means operable from exteriorly of the housing for sealing between the ends of the tubular loading member and the housing when said loading member is in alignment with the housing inlet conduit and outlet conduit and when said loading member is in alignment with the openable and closable access means and spaced from said inlet and outlet conduits.

3. A pipe line cleaner loading and clean-out device including, a housing having a chamber therein and having an inlet conduit and an outlet conduit communicating with said chamber, said housing being adapted to be connected with a fluid pipe line whereby fluid flowing through such pipe line may flow through the inlet conduit into

the chamber of the housing and outwardly therefrom through the outlet conduit, a loading member movable within the chamber of the housing and having a flow passage therethrough of a diameter substantially equal to the bore of the pipe, means operable from exteriorly of the housing for moving the loading member within the housing chamber to move the flow passage of said loading member into and out of communication with the inlet and outlet conduits, said loading member being movable completely out of alignment with the inlet and outlet conduits when the flow passage of the loading member is moved out of communication therewith, openable and closable means providing access to the flow passage of the loading member when the same is out of communication with the inlet and outlet conduits and fluids are flowing through the housing chamber exteriorly of the loading member to permit insertion of a cleaner member into said flow passage from exteriorly of the housing, whereby said cleaner member may pass from the flow passage of the loading member through the outlet conduit to the pipe line when the loading member is moved to position the flow passage in communication with the inlet and outlet conduits of the housing, sealing means adjustable from exteriorly of the housing for sealing between the ends of the tubular loading member and the housing when said loading member is in alignment with the inlet and outlet conduits and when said loading member is in communication with said openable and closable access means and spaced from the inlet and outlet conduits of the housing, and stop means operable from exteriorly of the housing and normally out of alignment with the inlet and outlet conduits of the housing and insertable into and retractable from alignment with said conduits in the housing chamber and adapted when in alignment with said conduits to prevent a cleaner member from passing through said housing from the inlet conduit thereof.

4. A pipe line cleaner loading and clean-out device including, a housing having a chamber therein and having an inlet conduit and an outlet conduit communicating with said chamber and adapted to be connected with a fluid pipe line, a tubular loading member movable in the chamber of the housing into and out of communication with the inlet and outlet conduits, means operable from exteriorly of the housing providing a fluid tight seal between the loading member and the inlet and outlet conduits when said loading member is in alignment with said conduits for directing all fluid flowing through the pipe line through said loading member, said means also being operable from exteriorly of the housing for sealing the bore of the loading member against admission of the fluids flowing through the pipe line when the loading member is out of alignment with the inlet and outlet conduits, and openable and closable means providing for access to the bore of said loading member from exteriorly of the housing when said loading member is sealed against admission of fluid to its bore.

5. A pipe line device adapted to be connected in a pipe line for the purpose of inserting a fluid operated cleaner member into said pipe line and removing such a cleaner member from said pipe line and including, a housing having a chamber therein and having inlet and outlet conduits communicating with said chamber whereby fluids flowing through the pipe line may flow into the housing chamber and outwardly therefrom, a

11

loading barrel having a flow passage therethrough and movable within the housing chamber into and out of alignment with the inlet and outlet conduits, whereby the flow passage through said loading barrel may be moved into and out of communication with said inlet and outlet conduits, means operable from exteriorly of the housing for sealing between one end of the loading barrel and the inlet conduit when the barrel is in alignment therewith, means also operable from exteriorly of the housing for sealing between the opposite end of the barrel and the outlet conduit when the loading barrel is in alignment therewith, both said means also being operable from exteriorly of the housing for closing off the flow passage of the barrel from admission of fluids thereto from the inlet and outlet conduits when the barrel is out of alignment with said conduit, whereby fluids flow from the inlet conduit through the housing chamber exteriorly of said loading barrel to the outlet conduit, and openable and closable means providing access to the flow passage through the loading barrel when the same is out of alignment with the inlet and outlet conduits and sealed against admission of fluids to its flow passage.

6. A pipe line cleaner loading and clean-out device including, a housing having a flow chamber therein and having an inlet conduit and an outlet conduit in axial alignment on opposite sides of the chamber communicating with said chamber and adapted to be connected with a fluid pipe line whereby fluids flowing through such pipe line may flow through the inlet conduit into the chamber of the housing and outwardly therefrom through the outlet conduit, a loading tube having a flow passage therethrough and inclined end surfaces and movable within the housing chamber into and out of alignment with the inlet and outlet conduits, means connected with such tube and operable exteriorly of the housing for moving the same in the housing chamber, seating rings at the inner ends of the inlet and outlet conduits, wedge means movable in the housing and adapted to be interposed between each inclined end of the tube and the adjacent seat ring to form a fluid tight seal therebetween when the tube is in axial alignment with the conduits, seat means within the housing chamber spaced from the inlet and outlet conduits and adapted to be engaged by the wedge means to seal between said seat means and the ends of the tube when said tube is in alignment with said seat means and out of alignment with the conduits, whereby the flow passage through the tube is sealed off to prevent fluids from within the housing chamber entering said flow passage, and means providing access to the flow passage of the loading tube when the same is out of alignment with the conduits, whereby a cleaner projectile may be inserted within the passage of the tube, said projectile being permitted to flow into the pipe line when the tube is moved to alignment with the inlet and outlet conduits of the housing.

7. A pipe line cleaner loading and clean-out device including, a housing having a chamber therein and having aligned inlet and outlet conduits adapted to be connected in a pipe line, tubular loading means movable in the housing chamber from a position in alignment with the inlet and outlet conduits to a position spaced from said conduits, whereby flowing fluids will travel from the inlet conduit through the housing chamber exteriorly of the loading means to

12

the outlet conduit, openable and closable means in the housing at a position spaced from the inlet and outlet conduits providing for access to the bore of the loading means when said means is out of alignment with said conduits to permit insertion of a cleaner projectile into the bore of the loading means while fluids are flowing through the housing exteriorly of said loading means, means for operating said loading means, and sealing means adjustable from exteriorly of the housing for sealing between the ends of the tubular loading means and the inlet and outlet conduits when said loading means is in alignment with said conduits and for sealing between the ends of said loading means and the housing when said loading means is in communication with the openable and closable access means in said housing and spaced from the inlet and outlet conduits, the housing chamber extending below the inlet and outlet conduits to provide a sump forming a trap for extraneous matter removed from the pipe line, whereby extraneous matter accumulating in said sump trap will not interfere with movement of the loading means in the housing chamber or with the flow of fluids through said chamber.

8. A pipe line cleaner loading and clean-out device including, a housing having a flow chamber therein and having inlet and outlet openings adapted to be connected in a pipe line, tubular loading means movable in the housing chamber into and out of alignment with the inlet and outlet openings of the housing, said housing chamber serving as a conductor for fluids from the inlet to the outlet thereof when said tubular loading means is moved out of alignment with said openings, openable and closable hatch means in the housing spaced from the inlet and outlet openings at a position providing for access to the bore of the tubular loading means when said loading means is out of alignment with the inlet and outlet openings of the housing to permit insertion of a cleaner projectile into the tubular loading means while fluids are flowing through the housing chamber exteriorly of the loading means, means for operating said loading means to move the same into alignment with the inlet and outlet openings to permit the projectile to flow from the loading means through the outlet of the housing into the pipe line and to retract said loading means from such position, and means operable from exteriorly of the housing providing a fluid tight seal between the ends of the tubular loading means and the inlet and outlet openings of the housing when said loading means is in alignment with said openings, said sealing means also being operable to provide a fluid tight seal between the ends of the tubular loading means and the housing when said loading means is in communication with the openable and closable hatch means in the housing and spaced from the inlet and outlet openings.

9. In a pipe line cleaner loading and clean-out device of the character set forth in claim 7, a conductor communicating with the sump trap of the housing for conducting accumulated extraneous matter from said sump trap to a remote point, valve means in said conductor for controlling flow therethrough, and a clean-out hatch in the wall of the housing below the conduits providing access to the lower portion of the housing chamber.

10. A pipe line cleaner loading and clean-out device including, a housing having a chamber therein and having aligned inlet and outlet conduits adapted to be connected in a pipe line, said

housing having sections forming chamber portions disposed radially from said conduits, one of said chamber portions being disposed below said conduits, tubular loading means having an axial flow passage therethrough and movable in another radially disposed chamber section in the housing into and out of alignment with the inlet and outlet conduits, means operable from exteriorly of the housing for moving said loading means, sealing means operable from exteriorly of the housing for sealing between the ends of said loading means and the housing when said loading means is in alignment with the inlet and outlet conduits and when said loading means is disposed in the radially extending chamber section out of alignment with said conduits, said sealing means preventing passage of fluids from the interior to the exterior of said loading means and in the reverse direction, a loading hatch in the wall of the housing section in which the loading means is adapted to be moved and providing for access to the flow passage of the loading means when the same is in said section and out of alignment with the conduits, the housing chamber section below the conduits forming a sump trap for extraneous matter flowing into said chamber from the pipe line, a conductor communicating with said sump trap section for conducting fluids therefrom to a remote point, valve means for controlling flow through said conductor, and a clean-out hatch in the wall of said lower section providing access to the interior thereof.

11. In a pipe line cleaner loading and clean-out device of the character set forth in claim 10, a valved conductor communicating with the housing chamber section in which the loading means is movable and positioned so as to communicate with the flow passage of the loading means when

5 said loading means is positioned in said chamber section for conducting fluids from the flow passage of said loading means to a point exteriorly of the housing chamber, a fluid by-pass conductor extending between the inlet conduit of the housing and the housing chamber section in which the loading means is movable, said conductor communicating with the interior of the housing chamber and being positioned to communicate with the flow passage of the loading means when said loading means is positioned in said chamber section, whereby pressure fluids may be conducted through said by-pass conductor from the inlet conduit to the interior of the housing or to the flow passage of the loading means for equalizing pressures therebetween, and valve means connected in the by-pass conductor for controlling flow therethrough.

20 WILLIAM H. ROBERTS.
